UNITED STATES PATENT OFFICE.

CHESTER C. DOTY, OF DANVILLE, AND CULLOM WATTERSON COFFEY, OF MONTICELLO,
KENTUCKY.

LICENSE PLATE.

Application filed June 2, 1922. Serial No. 565,328.

To all whom it may concern:

Be it known that we, CHESTER C. DOTY and CULLOM WATTERSON COFFEY, citizens of United States of America, and residents of 5 Danville, in the county of Boyle and State of Kentucky, and Monticello, in the county of Wayne and State of Kentucky, respectively, have invented new and useful Improvements in License Plates, of which the 10 following is a specification.

This invention relates to license plates for automobiles, and has for an object the provision of a plate which is permanent in its character, in so far as its main construction 15 is concerned; and it is an object of this invention to provide a novel plate which can be used indefinitely or during the existence of the automobile for which it is purchased, the said device being provided with novel 20 means whereby the "year" tag or indicia may be applied thereto and secured in place in a manner to insure it against being tampered with by unauthorized persons.

It is furthermore an object of this invention 25 to produce a license plate of the character indicated which protects and partially encloses a year plate or card which may be exposed through apertures in the plate, so that as the color of the "year" tag is changed, 30 it may be observed through the openings of the permanent plate. The year tag or plate can be made of comparatively inexpensive sheets and need not be of heavy gage metal or other material, so that its cost will be comparatively small as compared with the cost 35 of a new plate.

It is a further object of this invention to have a plate which will contain a record of the name of the automobile for which it is 40 purchased and on which it is to be used, as well as the number of the automobile, the capacity in passengers, the motor number, and the model number. The margin of the plate may also be used for carrying indicia such 45 as the county or town denoting the origin of the owner.

It is a still further object of this invention to produce a license plate of the character indicated in which the year plate or card 50 may be readily applied and in which it is secured by a sealed fastening that can be installed by an officer with an official sealing stamp, thus making it possible for an observer to detect whether the seal has been

broken or the plate has been tampered with. 55

It is a further object of this invention to produce a plate of the character indicated which will prove economical in use while it will possess the many advantages heretofore stated. 60

With the foregoing and other objects in view, the invention consists in the details of construction, and in the arrangement and combination of parts to be hereinafter more fully set forth and claimed. 65

In describing the invention in detail, reference will be had to the accompanying drawings forming part of this application wherein like characters denote corresponding parts in the several views, and in which— 70

Figure 1 illustrates a view in elevation of a license plate embodying the invention;

Figure 2 illustrates a top plan view thereof with the seal omitted;

Figure 3 illustrates a sectional view on the 75 line 3—3 of Fig. 1;

Figure 4 illustrates a sectional view on the line 4—4 of Fig. 1;

Figure 5 illustrates a view in elevation of the annual plate or card; and 80

Figure 6 illustrates a fragment of the rear side of the said plate.

In these drawings 10 denotes the marginal or frame-like structure of the face plate, provided with suitable slots or apertures for receiving fastenings by which the plate is secured to an automobile, the said frame being formed integral with numerals 12 that are shaped during the stamping of the material, to form the plate and license number. 85 It is to be understood, of course, that the numbers will be made different for each plate and these will constitute the main identifying indicia of the plate. In addition to the foregoing, the plate may be 90 stamped or pressed to display letters indicating the name of the automobile, as well as its serial number, and other indicia such as the passenger capacity, model and motor number as may be desired, and in addition, 95 the name of the town or county denoting the original of the owner may be stamped or otherwise displayed on the face of the plate.

The plate has apertures 13 and 14 for the 100 reception of apertured ears 15 and 16 respectively of a backing plate 17, which ears project through the apertures 13 and 14 as

- stated, and they are intended to receive a wire or other locking device 18 provided with a seal 19 which will prove effective to retain the parts in their assembled relation 5 and indicate if there has been any tampering with the license plate to a degree which will cause fracture of the seal. The back plate is preferably formed integral with the face plate and the plates may be separated a sufficient distance to permit the insertion between them of an annual license card or plate 20 which may contain indicia indicating the year for which the license plate is to be used and the State issuing the said 15 license.
- The back plate has a marginal flange 21 forming a seat for the edges of the annual plate or card, and the said plate or card is provided with slots 22 adapted to coincide 20 with the slots in the main plate through which the ears project, in order that the ears will also project through the annual plate or card to further guard against the indicia being changed.
- 25 The relation of parts is well shown in Fig. 1, and it will also be seen that a very attractive and efficient license plate results and that it carries indicating matter which would be of use for the authorities in making comparison to determine whether the license plate was being used on the proper automobile.
- A license plate embodying this invention would practically obviate the likelihood of 30 the transference of plates from one automobile to another, and would in many ways

safeguard not only the owner of the automobile, but the State using the said plates.

While the initial cost of the device might be slightly greater than the commonly used 40 license plate, the necessity for renewal of the main portions thereof being overcome, the cost in the subsequent years would more than compensate for the slightly increased initial expenditure. 45

We claim—

1. A license plate comprising a frame having integral numbers, the plate being cut away to produce the numbers with clearances therebetween, an annual plate back of 50 the first mentioned plate having indicia exposed through the openings produced in forming the numbers, and an element back of the frame for holding the said annual plate, including means for holding the element and plate in assembled relation to each other.

2. A license plate comprising a frame having integral numbers, the plate being cut away to produce the numbers with clearances therebetween, an annual plate located 60 back of the first mentioned plate having indicia exposed through openings formed in the first mentioned plate, the said first mentioned plate having slots, a back plate extending partially across the first mentioned plate, ears on the back plate extending through the apertures of the first mentioned plate, and a seal in the said apertures of the ears. 65
